UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

DRAFT-GEAR.

No. 900,024.

Specification of Letters Patent.

Patented Sept. 29, 1908

Original application filed November 17, 1905, Serial No. 287,864. Divided and this application filed March 17, 1906, Serial No. 306,615. Renewed September 9, 1907. Serial No. 392,044.

To all whom it may concern:

Be it known that I, HARRY T. KRAKAU, of Cleveland, Cuyahoga county, Ohio, have invented a new and useful Draft-Gear, of which the following is a full, clear, and exact description, reference being had to the accompanying drawings, forming part of this specification, in which—

Figure 1 is a plan view of a draft gear embodying my invention; Fig. 2 is a side elevation, partly in section, of the same; Fig. 3 is a vertical longitudinal section of the parts shown in Fig. 2, but on a larger scale; Fig. 4 is a plan view, partly in section, showing the pivotal connection of the coupler; and Fig. 5 is a detail view showing the connection between the springs and truck frame.

The present application is a division of my application Serial No. 287,864, filed November 17th, 1905.

My invention provides a draft-rigging in which the coupler is capable of swinging laterally through a wide range and is connected to the truck so as to be guided thereby positively into proper position.

The device can be used with success on passenger cars, and can also be applied to draft-rigging in a manner which will adapt them for use not only with passenger cars, but also with much greater efficiency than heretofore on freight car equipments. The advantages of such laterally-swinging draft gears are, that they relieve the cars from the great strain to which they are subjected when provided with laterally-fixed draft-gears, and also remove strain from the wheels, axles, and track, and thus increase the durability of the cars and effect a very considerable economy in the power required to move the trains.

The drawings show the preferred embodiment of my invention, but it will be understood by those skilled in the art that the parts and their arrangement may be modified in many ways and that some of the parts of the apparatus may be applied to use without the others.

In the drawings, 2 represents the car-coupler, which has a long rear extension preferably made in the form of a shank 3 which terminates at the end in a socket 4 for a vertical pivot-pin 5. For convenience, I prefer to make the coupler-shank in two

parts 3' and 3'', the rear portion 3' being provided with the socket 4 and being forked so as to fit the sides of the forward portion 3''. The socket 4 fits within a yoke 6 to which it is attached by the pivot-pin 5, and the yoke is mounted between the draft-irons 7, 7, followers 8 being set crosswise within the yoke and adapted to bear against stops 9 on the irons. A spring or springs 10 is interposed between the followers and these parts together constitute the draft rigging. A suitable tail-bolt which is a well known equivalent may be substituted for the yoke, frictional devices and the like may be employed, and the construction and arrangement of the springs and followers may be modified in many ways.

When the car is in service, the coupler and its shank will turn radially on the axis of pin 5, being guided by means described below, so that it will at all times be in approximately the central portion of the railway track. The draft rigging, however, is held from turning laterally by the car sills, and remains in the longitudinal axis of the car, and as the coupler is subjected to the pressure of buffing and draft, the forward follower will be forced back against the spring or the rear follower drawn forward against the spring as the case may be, the forward stops 9 resisting the force of draft and the rear stops 9 resisting the force of buffing.

As shown in Fig. 5 the forward follower 8 preferably projects forwardly somewhat and is provided with a curved face against which a correspondingly curved surface on the end of the coupler-shank bears, so as to afford a bearing for the coupler-shank in all positions of lateral adjustment of the shank and compression of the spring.

To guide the coupler-shank and to hold it substantially at the center of the track, I provide it with guiding-rods shown in Figs. 1, 2, 3 and 4, which are made with telescopically-arranged sections having interposed springs 11. At their rear ends these rods are connected by ball-and-socket joints 12 to brackets 13 at the ends of the truck, and at their forward ends the rods are connected by ball-and-socket joints 14 with an elbow-lever or like connection 15, mounted at the middle on a vertical pin 16 which projects downwardly from the coupler-shank and is

preferably connected therewith by a pad 17 and bolts 18. The pin may, however, be made integral with the coupler-shank, or otherwise secured thereto. The elbow-lever connects the guiding-rods to the coupler-shank in such manner that tension exerted upon it on either side will turn it and keep its arm on the other side in the proper line, and the ball-and-socket joints afford 10 the necessary flexibility to the parts.

To insure the guiding of the coupler substantially to the center of the track, I locate the pivotal axis 5 back of the front end of the truck frame and the point 16 in advance of 15 the truck frame.

I claim:—

1. A draft gear having its spring rigging carried by the car-frame, and its draw-bar guided by the car-truck and pivotally connected to the spring rigging at a point back of the front end of the truck frame; substantially as described. 20
2. A draft gear having its spring rigging carried by the car-frame, and its draw-bar connected with the car-truck at a point on the draw-bar forward of the truck frame 25

and pivoted to the spring rigging at a point back of the front end of the truck-frame; substantially as described.

3. A laterally-swinging draft-gear having 30 guiding connections with the truck composed of members with ball - and - socket joints.

4. A laterally-swinging draft-gear having 35 guiding connections with the truck composed of members with universal joints.

5. A laterally-swinging draft-gear having 40 guiding connections with the truck composed of members with an intermediate elbow-lever pivoted on the draft-gear.

6. A laterally-swinging draft-gear having 45 guiding connections with the truck composed of members with an intermediate pivotally mounted connection on the draft-gear.

In testimony whereof, I have hereunto set my hand.

HARRY T. KRAKAU.
